[57] CLAIM

The ornamental design for a fly trap, as shown and described.

DESCRIPTION

FIG. 1 is a perspective view of the fly trap showing my new design wherein the front and top views and left side elevation are visible.

FIG. 2 is a left side elevation thereof: the right side elevation is a mirror image thereof.

FIG. 3 is a back elevation thereof.

FIG. 4 is a bottom view thereof.

FIG. 1

FIG. 2

FIG. 3

FIG. 4
